D. Thompson.

By Attorney

UNITED STATES PATENT OFFICE.

DAVID THOMPSON, OF MECHANICSVILLE, CONNECTICUT.

DESIGN FOR A GAME-BOARD.

54,292.

Specification for Design.

Patented Dec. 9, 1919.

Application filed May 17, 1919. Serial No. 297,971. Term of patent 3½ years.

To all whom it may concern:

Be it known that I, DAVID THOMPSON, a citizen of England, residing at Mechanicsville, in the county of Windham and State of Connecticut, have invented a new, original, and ornamental Design for Game-Boards, of which the following is a specification, reference being had to the accompanying drawing, forming part thereof.

The figure is a plan view, showing my new design.

I claim:

The ornamental design for a game board, as shown.

DAVID THOMPSON.
